UNITED STATES PATENT OFFICE.

THOMAS B. RICE AND FRED W. WILLIAMS, OF SANTA MARIA, CALIFORNIA.

CIGARETTE CASE.

Application filed September 5, 1925. Serial No. 54,752.

This invention relates to an improved cigarette case and seeks, among other objects, to provide a device of this character wherein, when the case is opened, a cigarette will be ejected, so that the cigarette may be readily grasped, while the lighter of the device will be simultaneously ignited, whereby the cigarette may be lighted.

The invention seeks, as a further object, to provide a device embodying a spring pressed lid, and wherein the manual actuation of the catch to release the lid will also serve to operate a trip for releasing one of the ejectors to eject a cigarette, while, also, the actuating member of the lighter will be released by the lid so that the lighter will be simultaneously ignited.

And the invention seeks, as a still further object, to provide a device wherein the trip mechanism will release the ejectors one at a time so that each time the lid is opened, a single cigarette will be ejected.

Other objects of the invention not above specifically mentioned will appear as the description proceeds.

In the accompanying drawings:

Figure 1 is a front elevation of our improved cigarette case.

Figure 2 is a vertical sectional view 30 through the device.

Figure 3 is a transverse sectional view taken through the lid of the device.

Figure 4 is a transverse sectional view taken through the lower portion of the case 35 and particularly showing the trip mechanism.

Figure 5 is an enlarged fragmentary vertical sectional view particularly showing one of the ejector catches and illustrating the manner in which the trip arms of the trip 40 shaft are adapted to engage said catches for releasing the catches.

Figure 6 is a detail sectional view showing the staggered relation of the arms on 45 said shaft.

Figure 7 is an enlarged detail vertical sectional view particularly showing the actuating latches of the trip mechanism.

Figure 8 is a vertical sectional view 50 through the case on the line 8-8 of Figure 3, looking in the direction indicated by the arrows, and particularly showing the lighter.

In carrying the invention into effect, we 55 employ a flat oblong casing 10 which is normally closed at its upper end by a lid 11

suitably hinged to the casing, and mounted within the casing is a plurality of vertically disposed tubular cigarette holders 12. These holders are suitably fixed at their upper ends to a top plate 13 which is appropriately secured within the upper end of the casing and, as brought out in Figures 2 and 3, said plate terminates short of one side wall of the casing to define a lighter compartment 14 open at its upper end. The holders 12 are arranged in parallel rows, and disposed within the lower ends of said holders are ejector springs 15 to the upper ends of which are secured ejector plates 16 loosely fitting in the holders. Formed in the holders, near the lower ends thereof, as shown in Figure 5, are slots 17, and fixed to the holders below said slots are spring catch members 18, the laterally bent heads of which project freely through said slots to normally engage over the plates 16 for holding said plates depressed. The free ends of said heads are directed outwardly through said slots to provide spring fingers 19 and, as will be observed, said fingers are downturned at their outer ends to form lips 20. The holders are each of a diameter to freely receive a cigarette, the cigarettes being conventionally illustrated at 21, and by pushing the cigarettes downwardly within the holders, the plates 16 may be depressed to engage beneath the catch members 18. Thus, the cigarettes are normally supported by said plates to project at their upper ends slightly above the upper ends of the holders, and fixed within the holders are stop rings 22 for limiting the plates 16 in their upward movement when released by the catch members.

Extending horizontally between the rows of holders 12 near the lower ends thereof is a rotatable shaft 23, and fixed to said shaft, at longitudinally spaced points, to cooperate with the fingers 19 of the catch members 18, are radial arms 24. The arms 24 are uniformly staggered circumferentially of the shaft to successively cooperate with the fingers, in turn, and fixed to one end of said shaft, as particularly shown in Figure 2, is a beveled gear 25. Extending vertically of the casing at the adjacent side thereof is a shaft 26, and fixed to the lower end of said shaft is a beveled gear 27 meshing with the gear 25, while to the upper end of said shaft is fixed a beveled gear 28. Extending horizontally between the rows of holders 12 near the upper ends thereof is a shaft 29,

and fixed to one end of said shaft is a bevelled gear 30 meshing with the gear 28. Fixed to the shaft 29 medially thereof, as shown in detail in Figure 7, is a ratchet 31, the teeth of which correspond in number and spacing with the number and spacing of the arms 24 of the shaft 23, and fixed to the plate 13 to cooperate with said ratchet is a spring pawl 32 for locking the ratchet 31 against retrograde movement. Slidable through the front wall of the casing 10 opposite the ratchet 31 is a hollow cylindrical plunger 33 provided at its inner end with a flange 34 for limiting the plunger against outward displacement, and bearing against said flange is a spring 35 normally holding the plunger retracted. At its upper side the plunger is provided with a notch 36 to accommodate the forward lower margin of the lid 11, and projecting into said notch freely through an opening in said margin of the lid is a catch 37 normally securing the lid closed. Fixed at one end to the flange 34 of the plunger is a spring pawl 38, the opposite end of which is disposed to cooperate with the teeth of the ratchet 31.

As will now be seen in view of the foregoing, when the plunger 33 is depressed, the lid 11 will be released while the ratchet 31 will be turned a step by the pawl 38. The shaft 23 will, therefore, be correspondingly rotated so that one of the arms 24 of said shaft will be advanced against the lip 20 of the finger 19 of one of the catch members 18, as shown in Figure 5, for retracting said catch member and releasing one of the ejector plates 16. The travel of the arm of the shaft 23 will be sufficient to flex the finger of the catch member and cause the arm of said shaft to ride out of engagement with the lip of said finger for freeing the catch member. However, immediately upon the release of the ejector plate 16, said plate will be shifted upwardly by its spring 15, for ejecting one of the cigarettes 21 upwardly within its holder so that said cigarette may be readily grasped. Thus, each time the shaft 23 is actuated, one of the ejectors will be released for ejecting a cigarette and, of course, as each of the arms 24 of the shaft 23 moves out of engagement with the finger 19 of one of the catch members, the next successive arm of the shaft will be brought into position for engagement with the lip 20 of the finger of the next successive catch member so that when the last cigarette is ejected and the holders are refilled, a cigarette will, when the catch 33 is next actuated, be ejected from the holder first emptied.

Suitably mounted within the compartment 14 of the casing 10 is a fuel receptacle 38' from which projects a wick 39, and fixed to the side wall of the receptacle is a tubular casing 40 slidably accommodating a py-

rophoric stick 41 beneath which is disposed a spring 42. Projecting from the back wall of the casing within the upper portion of said compartment are spaced arms 43 journaling a shaft 44, and fixed to the shaft between said arms is a friction disc 45 engaged by the stick 41. The shaft 44 also carries a ratchet 46. Projecting from the back wall of the casing within the lower portion of the compartment 14 are vertically spaced guides 47, and slidable through said guides is a plunger rod 48 pressed upwardly by a spring 49. Formed on or otherwise secured to the lid 11 to normally bear against the upper end of said rod is an arm 50 and projecting from the upper end portion of the rod is an arm 51 to which is pivoted a rack bar 52 urged by a spring 53 to cooperate with the ratchet 46.

As will now be perceived, when the plunger 33 is depressed and one of the ejectors is released to eject a cigarette, as previously described, the rod 48 will, upon the release of the lid 11 by the catch 37, be shifted upwardly by the spring 49 for swinging the lid to open position. Coincidently, the rack bar 52 will coact with the ratchet 46 for turning the friction disc 45 so that said disc will be caused to cooperate with the pyrophoric stick 41 for lighting a flame at the upper end of the wick 39. Thus, the cigarette ejected may be readily lighted.

Having thus described the invention, what we claim is:

1. A cigarette case including a casing having a plurality of tubular holders therein to receive cigarettes, spring pressed ejectors freely movable in said holders for ejecting the cigarettes, separate catch members normally securing said ejectors retracted, and means to coact with said catch members successively for successively releasing said ejectors.

2. A cigarette case including a casing having a plurality of tubular holders therein to receive cigarettes, spring pressed ejectors freely movable in said holders for ejecting the cigarettes, separate catch members normally securing said ejectors retracted, means to coact with said catch members successively for successively releasing said ejectors, a spring actuated lid normally closing the casing, and means for releasing the lid and actuating said first mentioned means.

3. A cigarette case including a casing having a plurality of tubular holders therein to receive cigarettes, spring pressed ejectors freely movable in said holders for ejecting the cigarettes, separate catch members normally securing said ejectors retracted, means to coact with said catch members successively for successively releasing said ejectors, a lid normally closing the casing, a lighter, igniting means for the lighter, spring pressed actuating means for said igniting means and

- normally tending to open the lid, and means for releasing the lid and actuating said first mentioned means whereby the lighter will be ignited when the lid is opened and a 5 cigarette is ejected.
4. A cigarette case including a casing having a plurality of tubular holders therein to receive cigarettes, spring pressed ejectors freely movable in said holders for ejecting 10 the cigarettes, separate catch members normally holding said ejectors retracted and provided with fingers, and means to coact with said fingers for retracting said catch members successively and successively re- 15 leasing said ejectors.
5. A cigarette case including a casing having a plurality of tubular holders therein to receive cigarettes, spring pressed ejectors freely movable in said holders for ejecting 20 the cigarettes, separate catch members normally securing said ejectors retracted and provided with fingers, a rotatable shaft having arms staggered to coact with said fingers successively for retracting the catch mem- 25 bers and successively releasing said ejectors, and mean for rotating said shaft step by step.
6. A cigarette case including a casing having a plurality of tubular holders therein to receive cigarettes, spring pressed ejectors freely movable in said holders for ejecting 30 the cigarettes, separate catch members normally securing said ejectors retracted and provided with fingers, a rotatable shaft having arms staggered to coact with said fingers successively for retracting the catch mem- 35 bers and successively releasing said ejectors. a spring actuated lid for the casing, and means normally securing the lid closed and 40 operable to release the lid and rotate said shaft step by step.
7. A cigarette case including a casing hav-
- ing a plurality of tubular holders therein to receive cigarettes, spring pressed ejectors freely movable in said holders for ejecting 45 the cigarettes, separate catch members normally securing said ejectors retracted and provided with fingers, a rotatable shaft having arms staggered to coact with said fingers successively for retracting the catch mem- 50 bers and successively releasing said ejectors, a second shaft having driving connection with said first mentioned shaft and provided with a ratchet, a spring actuated lid for the casing, and a plunger having a catch 55 normally securing the lid closed and provided with a pawl to coact with said ratchet, the plunger being movable for releasing the lid and actuating said ratchet for turning said first mentioned shaft step by step. 60
8. A device of the character described including a casing having a plurality of article holders therein, spring pressed ejectors freely movable in said holders for ejecting articles from the holders, separate means 65 normally securing said ejectors retracted, and means rotatable to coact with said first mentioned means successively for successively releasing said ejectors.
9. A device of the character described in- 70 cluding a casing having a plurality of article holders therein, spring pressed ejectors freely movable in said holders for ejecting articles therefrom, means normally securing said ejectors retracted, means rotatable to 75 coact with said first mentioned means suc- cessively for successively releasing said ejector, a spring actuated lid normally closing the casing, and means for releasing the lid and actuating said second mentioned means. 80

In testimony whereof we affix our signatures.
